UNITED STATES PATENT OFFICE.

PURCY FORBES, OF LAKEWOOD, WISCONSIN, ASSIGNOR OF ONE-HALF TO GEORGE L. YOUNG, OF LAKEWOOD, WISCONSIN.

RAIL-JOINT.

1,201,815.

Specification of Letters Patent.

Patented Oct. 17, 1916.

Application filed June 2, 1916. Serial No. 101,304.

To all whom it may concern:

Be it known that I, PURCY FORBES, a citizen of the United States of America, residing at Lakewood, in the county of Oconto and State of Wisconsin, have invented certain new and useful Improvements in Rail-Joints, of which the following is a specification, reference being had therein to the accompanying drawing.

10 The invention relates to rail joints, whereby abutting rails of a track may be interconnected in an efficient and simple manner.

The principal object of the invention consists therein to provide a rail joint free of 15 bolts, which may be readily assembled or taken apart.

A further object of the invention consists in providing a rail joint which simultaneously acts in the capacity of an anti-creeper, thereby preventing undue displacement of the two rail ends under the influence of heavy loads, but permitting restricted movement in longitudinal direction due to changes of temperature.

25 A further object of the invention aims at the provision of a joint which consists of comparatively few parts of simple construction.

With these and other objects in view, 30 which will become apparent by reference to the drawing and the specification, the preferred form of the invention consists in the novel arrangement and construction of the parts, as described in the specification and specifically pointed out in the appended claims.

In the accompanying drawing, Figure 1 is a side view of the ends of two rails to which the joint in accordance with the invention is applied. Fig. 2 is a section on line A—A of Fig. 1. Fig. 3 is a section taken on line B—B of Fig. 1. Fig. 4 is a perspective view of one of the upper fish plates. Fig. 5 is a perspective view of one of the lower fish plates, which simultaneously serves as an anti-creeping means. Fig. 6 is a perspective view of a locking block to hold the parts in assembled position.

Referring to the drawing and particularly 50 to Fig. 1, 1 designates the ends of two rails which are separated from one another by a narrow distance, as will be readily understood. At the under-side of the rail head 2, longitudinally of the fillet, an under-cut 55 groove 3 is provided, while the flange 4 of

the rails is equipped with a rectangular aperture 5 at a suitable distance from the end and close to the web for a purpose hereinafter indicated. A fish plate 6, substantially of rectangular form, is provided with extensions 7 which are adapted to enter the rectangular apertures 5 of two adjoining rail ends. The middle portion of the fish plate 6 is thicker than the remaining part, whereby a rectangular lug or projection 8 is formed. A similar plate 9 is placed directly above the plate 6 and represents the upper part of the fish plate which overlaps both rail ends. The plate 9 also has an enlarged middle portion 10 in the form of a rectangle which, however, projects beyond its lower edge, but originates somewhat below its upper edge. The middle portion 8 of the fish plate 6 also originates slightly below the upper edge thereof, and its lower edge is substantially flush with the lower edge of the plate.

The locking member 11 is of oblong form and its lower part is forked, whereby prongs 12, 12 are formed between which a sliding block 13 is arranged to reciprocate in vertical direction. At the inside of the prongs 12 grooves 14 are provided adapted to receive lugs 15 of the sliding block 13, whereby the latter is guided in its vertical movements. The sliding block 13 is formed at its lower end with an extension 16 of suitable dimensions, and the locking member 11 is also formed with an integral extension 17 at its upper end adapted to enter the groove 3 of the rail head. In order to join the two rail ends which, of course, are arranged in operative position, the fish plate 6 is arranged as indicated in Fig. 1 so that its flat face engages the webs of the rail ends, while its extensions 7 enter the rectangular apertures 5 provided in the rail flanges. Thereupon the auxiliary fish plate 9 is placed above the plate 6 in such manner that the portion 10 thereof rests upon the upper edge of the plate 6 and upon portion 8 of the same, as will be readily understood by reference to Fig. 2.

It is, of course, obvious that the upper edge of the plate 9 enters the grooves 3 of the two rail ends and by reason of the fact that the extensions 7 enter the rectangular apertures the fish plates are assembled and automatically held in place. Subsequently the locking member 11 is applied in order to 113

prevent the fish plates from leaving their operative position which would be the case when the rail ends are subjected to jars, vibrations, or the like. When locking the 5 plates in position two locking members 11 on each side of the rail ends are mounted so that the extension 17 also enters the groove 3 of the rail heads and has a wedge-like engagement with the upper fish plate 10 9. During this operation the sliding block 13 is held in its upper or raised position until the locking member occupies its operative position, whereupon the sliding block 13 is permitted to drop by its own gravity, 15 whereupon the tongue 16 enters the aperture 5 and engages the extension 7 of the fish plate 6.

From the foregoing it is obvious that the rail joint consists of relatively few parts 20 of simple and cheap construction which may be assembled and locked in position without the employment of bolts, rivets, or the like, and providing notwithstanding this a highly efficient and lasting rail joint which effectively prevents the rails from executing relative movements with respect to each other in vertical direction.

It is apparent that the several parts of the rail joint may be altered and it is my 30 intention not to bind myself specifically to the illustration shown by way of example, but, on the contrary, want to avail myself of any departures which fairly fall within the scope of my invention, as indicated in 35 the appended claims.

I claim:

1. In combination with abutting rail ends provided with apertures in the flanges, fish plates overlapping the webs of said rail ends 40 and entering with extensions said apertures, additional fish plates arranged between said first mentioned fish plates and the rail heads, and means for locking all of said fish plates to said rail ends.
2. A rail joint comprising in combination with rail ends, fish plates overlapping the webs of said rail ends, means formed on said fish plates to prevent creeping of said rails, additional fish plates arranged between said first mentioned fish plates and the rail heads, and means for locking all of said fish plates to said rail ends.
3. In combination with abutting rail ends provided with apertures in the flanges, fish 55 plates overlapping the webs of said rail ends and entering with extensions said apertures, additional fish plates arranged between said first named fish plates and the rail heads, said first and second named fish plates being formed with projections to form an interfitting joint, and means for simultaneously locking all of said fish plates to said rail ends.
4. In combination with abutting rail ends 65 provided with apertures in the flanges and

with grooves at the under side of the rail heads, fish plates overlapping the webs of said rail ends and entering with extensions said apertures, additional fish plates arranged between said first named fish plates 70 and the rail heads, said additional fish plates entering said grooves in the rail heads, and means for locking all of said fish plates to said rail ends.

5. In combination with abutting rail ends 75 provided with apertures in the flanges and with grooves at the under side of the rail heads, fish plates overlapping the webs of said rail ends and entering with extensions said apertures, additional fish plates arranged between said first named fish plates 80 and the rail heads, said additional fish plates entering said grooves in the rail heads, and means for simultaneously locking all of said fish plates to said rail ends. 85

6. The combination with rail ends provided with apertures in the flanges and with grooves at the under side of the rail heads, of fish plates engaging the webs of said rail ends, and locking members projecting into 90 said grooves and adapted to enter said apertures for securing said fish plates in position.

7. The combination with rail ends provided with apertures in the flanges and with 95 grooves at the under side of the rail heads, of fish plates engaging the webs of said rail ends, and locking members projecting into said grooves and adapted to enter with an extensible portion said apertures for securing 100 said fish plates in position.

8. The combination with rail ends provided with apertures in the flanges and with grooves at the under side of the rail heads, of fish plates engaging the webs of said rail ends, and locking means comprising an oblong block provided with a guideway, and a sliding block reciprocatingly fitted in said guideway, said oblong block entering said grooves, and said sliding block being adapted 110 to enter said apertures, substantially as described.

9. The combination with rail ends provided with apertures in the flanges and with grooves at the under side of the rail heads, 115 of fish plates engaging the webs of said rail ends, and locking means for securing said fish plates in position, said means comprising a block being forked at one end, grooves formed in the inside of the prongs, and a 120 block slidingly fitted with tongues in the grooves of said prongs and adapted to enter one of the apertures in the flanges, said first named block entering one of said grooves in the rail heads, substantially as described. 125

10. The combination with rail ends provided with apertures in the flanges and with grooves at the under side of the rail heads, of fish plates engaging the webs of said rail heads and entering with extensions said 130

- apertures, and locking members extending at right angles to said fish plates and entering with extensions said grooves and said apertures, substantially as described.
- 5 11. In combination with abutting rail ends provided with apertures in the flanges and with grooves at the under side of the rail heads, fish plates overlapping the webs of said rail ends and entering with extensions said apertures, additional fish plates arranged between said first named fish plates and the rail heads, said additional fish plates entering said grooves in the rail heads, and locking means comprising an oblong block provided with a guideway, a sliding block reciprocatingly fitted in said guideway, said oblong block entering said grooves and said sliding block being adapted to enter said apertures, substantially as described.
- 10 12. In combination with abutting rail ends provided with apertures in the flanges, fish plates overlapping the webs of said rail ends and entering with projections said apertures and said grooves at the under side of the rail heads, additional fish plates arranged between said first named fish plates and the rail heads, and locking members extending at right angles to said fish plates and engaging the same, said locking members entering said grooves and extending with an extensible portion into said apertures, substantially as described.
- 15 13. The combination with abutting rail ends provided with grooves at the under side of the rail heads and with apertures in the flanges, of fish plates entering with projections said apertures, thereby serving as anti-creeping means, and locking means for securing said fish plates in position, said locking means entering said flange apertures and projecting into said grooves to maintain engagement with said fish plates, substantially as described.
- 20 14. The combination with rail ends provided with apertures in the flanges and with grooves at the under side of the rail heads, of fish plates engaging said rail ends, and locking means abutting said fish plates and extending in vertical direction, said locking means being adapted to enter said apertures and said grooves whereby said fish plates are detachably secured in operative position.
- 25 In testimony whereof I hereunto affix my signature.

PURCY FORBES.
